UNITED STATES PATENT OFFICE.

HERBERT E. ENSLIN, OF MALDEN, MASSACHUSETTS, ASSIGNOR TO UNITED SHOE MACHINERY COMPANY, OF PATERSON, NEW JERSEY, A CORPORATION OF NEW JERSEY.

THREAD-END-FASTENING MACHINE.

1,246,075.

Specification of Letters Patent. Patented Nov. 13, 1917.

Application filed December 4, 1913. Serial No. 804,616.

To all whom it may concern:

Be it known that I, HERBERT E. ENSLIN, a citizen of the United States, residing at Malden, in the county of Middlesex and 5 State of Massachusetts, have invented certain new and useful Improvements in Thread-End-Fastening Machines; and I do hereby declare the following to be a full, clear, and exact description of the invention, such as 10 will enable others skilled in the art to which it appertains to make and use the same.

This invention relates to machines for fastening or tying the free ends of the thread left at the extremities of a finished seam.

15 The machine embodying the present invention is particularly designed for fastening the free ends of thread at the extremities of a seam by which a series of buttons is attached to the upper of a shoe. It is to 20 be understood, however, that the machine is not limited to such use, but that it may be employed in fastening the free ends of the thread at the extremities of various kinds of seams.

25 After the seam by which a series of buttons is attached to the upper of the shoe is completed, a free end of thread is left at each end of the seam projecting from the upper on the side thereof opposite that on 30 which the buttons are attached. Unless these free ends of thread are fastened in some manner, the strain upon the buttons at the ends of the seam, when the shoe is buttoned, will pull the ends of the thread

35 through the work. In order to fasten each of the free ends of the thread, it has been the practice to tie the free end of the thread about one of the thread loops of the seam adjacent the end of the seam. One method 40 of fastening the end of the thread has been to lay the free thread end across one of the adjacent loops of the seam and then to draw the end of the thread back through said loop on the side of the free thread nearer 45 the end of the seam. This operation, which has heretofore been performed by hand, requires some skill and consumes considerable time. On account of the small size of the loop of thread of the seam, it is quite difficult to draw the free end of the thread between this loop and the upper.

The primary object of the present invention is to produce a thread end fastening machine by which the free end of the thread

55 at the end of a finished seam may be fastened more quickly and easily than can be done by hand.

With this object in view, the invention comprises a device for drawing the free end of the thread beneath a loop of thread forming part of the seam, which is constructed for insertion between said loop and the upper or material in which the seam is formed and means is provided for relatively moving said device and the work to withdraw 60 the device from beneath the thread loop so as to draw the free end of the thread beneath the loop. In the preferred form of 65 the invention, said device comprises relatively movable jaws which are opened and closed to receive and grip the thread.

A further feature of the invention contemplates the provision of a thread finger about which the free thread is drawn in placing the work in fastening position so as 70 to insure a predetermined length of the free thread between the work and the thread drawing device. This predetermined length of free thread enables the device by which 75 the thread is drawn beneath the loop of the seam to be withdrawn entirely from the loop, and insures the tightening of the knot formed.

80 Other features of the invention consist of certain novel constructions, arrangements 85 and combinations of parts, the advantages of which will be obvious to those skilled in the art from the following description.

In the drawings illustrating a machine embodying the various features of the invention in their preferred forms, Figure 1 is a view in front elevation of the machine; Fig. 2 is a view in side elevation of the machine looking from the left; Fig. 3 is a view in plan of the machine; Fig. 4 is a view in sectional elevation of the machine taken substantially on the line 4—4 of Fig. 1; Fig. 5 is a view in sectional elevation taken substantially on the line 5—5 of Fig. 1, with a portion of the mechanism broken away; 90 Fig. 6 is a detail view in front elevation of a portion of the thread cutting device; and Figs. 7, 8, 9 and 10 are diagrammatic views 95 illustrating the several steps in the thread fastening or tying operation.

100 The machine is provided with a thread gripping device for gripping the free end of the thread which comprises relatively

movable thread gripping jaws indicated respectively at 2 and 4, the forward extremities of which are so shaped that when the jaws are closed the gripping device may be readily inserted beneath a loop of thread forming part of a seam. When the gripping device has been inserted beneath this loop of thread, the jaws are opened to receive the free end of the thread between them, and after the thread has been placed between the jaws thereof, the jaws are closed to grip the thread. The jaw 2 of the gripping device is fixed, and is carried on the forward end of an arm 6 which is mounted for forward and rearward adjustment on the frame, so that the gripping device may be placed in proper position with relation to the other parts of the machine to co-operate therewith. The arm 6 is provided with a tongue which fits in a suitable groove in the frame, and the arm is secured in adjusted position on the frame by means of a bolt 8 passing through a slot in the frame and screwed into the arm. The movable jaw 4 of the gripping device is carried upon the forward end of a lever 10 which is pivoted on a stud 12 secured in an upwardly extending ear on the arm 3. The lever 10 carries a roll 14 at its rear end, and is actuated to open the jaws of the gripping device to receive the thread, by the movement of an arm 16 pivoted on a shaft 18 and provided with a forked forward end which embraces the roll 14. The arm 16 is actuated by means of a lever 20 also pivoted on the shaft 18 and carrying a cam roll 22 which engages a cam groove 24 in a cam disk 24^a secured to the main shaft 26 of the machine. The lever 20 is connected with the arm 16 by means of a bolt 28 passing loosely through said arm and screwed into a forwardly extending arm 30 on the lever 20, a nut 32 being threaded on the upper end of the bolt to engage the upper face of the arm 16. This connection between the arm 16 and the lever 20 is such that the arm is actuated by the lever only in a direction to open the jaws of the gripping device, and provides for lost motion between the arm and the lever when the thread has been gripped by the gripping jaws. By adjusting the nut 32 on the bolt 28, the operation of the gripping device may be regulated. The movable jaw of the gripping device is actuated to grip the thread by means of a coiled spring 34 which insures the closing of the jaws to grip the thread in a reliable manner regardless of the diameter of the thread which is passed between them.

In Figs. 7 to 10 inclusive is shown a section of an upper having a series of buttons attached thereto by a seam formed by a button sewing machine of a type now in common commercial use. It has not been considered necessary to illustrate the seam for

mation on the button side of the upper, since the manner in which the machine of the present invention operates to fasten the end of the thread depends only on the seam formation on the inside of the upper or the side opposite that on which the buttons are attached. It will be noted from an inspection of these figures that on the inner face of the upper, at the end of the seam, there is a relatively short loop *b* and a long loop *c*, and that the free end of the thread emerges from the work on the upper side of the long loop *c* and at some distance from the outer or left-hand end thereof. In presenting the work to the gripping device, the upper is held by the operator with the end of the seam at the left and with the free end of the thread emerging from the work on the side of the long loop *c* away from the operator, and the work is then manipulated to insert the gripping device, the jaws of which are at that time closed, beneath the long loop *c*, as shown in Fig. 7. The operator then grasps the free end of the thread and draws it beneath the gripping device and over the work to form a loop, as indicated at *d*, one leg of which lies across the loop *c*, as shown in Fig. 8. In order to insure a length of the loop *d* in the free end portion of the thread, sufficient to enable the gripping device to be drawn free from the loop *c* and the thread to be fastened properly, an abutment or finger is provided about which the end of the thread is drawn in placing it in fastening position. In the illustrated construction, this abutment consists of a downwardly projecting finger 38 formed on a plate mounted for forward and rearward adjustment on the arm 6 and secured thereto by means of a screw 40. The provision for adjustment of this abutment or finger enables the length of the loop formed in the free end portion of the thread to be varied to suit the requirements for the satisfactory fastening of the end of the thread.

When the free end of the thread has been placed by the operator in the position illustrated in Fig. 8, the jaws of the gripping device are opened to receive the thread, and a thread receiving hook is projected between said jaws, which, after receiving the thread, retracts to draw the end of the thread between the gripping jaws. This hook is indicated at 42, and is mounted to reciprocate longitudinally in a direction transverse to the gripping device. Before the jaws of the gripping device are opened, the hook 42 occupies the position illustrated in Fig. 7, with relation to the gripping device. When the jaws of the gripping device have opened, the hook 42 is projected between said jaws to bring the hook into the position illustrated in Fig. 8. The end of the thread is then placed by the operator within the hook,

after which the hook is retracted to its initial position, thereby drawing the end of the thread between the jaws of the gripping device, as illustrated in Fig. 9. The hook 42 is secured to the lower side of a slide 44 which is mounted to slide laterally with relation to the gripping device in guides formed in a forwardly projecting arm 46 on the frame of the machine. The hook is secured to the slide by passing the shank of the hook through a bore in a block 48, and through a registering bore in the head of a screw 50 which passes through both the block and the slide. A nut 52 is threaded on the upper end of the screw, and the hook is securely held in position with relation to the block and the slide by tightening this nut. Upon loosening the nut the hook may be adjusted with relation to the slide. The slide 44 is reciprocated in its guides to give the required movements to the hook during the operation of the machine by a cam actuated lever 54 pivoted on a stud 56, and provided with a fork at its forward end which embraces a cylindrical portion of the nut 52, said lever being provided with a cam roll 58 engaging in a cam groove 60 in a cam disk 62 mounted on the main shaft 26.

When the free end portion of the thread has been drawn between the jaws of the gripping device, the jaws of the gripping device are closed to grip the thread, and the gripping device and the work are then moved relatively to withdraw the gripping device from beneath the loop of thread under which it lies to draw the portion of the thread gripped between the jaws of the gripping device beneath the said loop on the side of the end portion of the thread nearer the end of the seam, and to draw the thread taut between the gripping devices and the work to complete the fastening or tying operation. The relative movement between the gripping device and the work to withdraw the gripping device from the loop of the seam is preferably produced by advancing the work while the gripping device is stationary. In the construction illustrated, the means for advancing or moving the work forwardly with relation to the gripping device comprises a pusher 64, the upper end of which is forked and embraces the arm 6 and the lever 10 upon which the respective gripping jaws of the gripping device are carried. After the end portion of the thread is drawn between the jaws of the gripping device, and the said jaws are actuated to grip the thread, the pusher 64 is advanced to engage the work and to push the work forwardly with relation to the gripping device, thereby withdrawing the gripping device from the loop of thread beneath which it was inserted, and drawing the free end of the thread beneath the loop. The forward movement of the pusher is continued

until the thread is drawn taut between the gripping jaws and the work. Fig. 10 illustrates the relative positions of the gripping device and pusher at the completion of this step in the operation, and shows clearly the manner in which the free end portion of the thread is drawn about the loop c to fasten the thread end. The character of the fastening will depend, however, upon the character of the seam formation, and also upon the position in which the end portion of the thread between the gripping device and the work is placed with relation to the gripping device and the thread loop of the seam.

The pusher 64 is carried on the forward end of a slide 66 which is mounted to slide forwardly and rearwardly in suitable guides formed in the frame of the machine. The mechanism for giving the required movements to the pusher during the operation of the machine comprises a link 68 connecting the rear end of the slide 66 with one arm of a bell crank lever 70 pivoted on a shaft 72. The other arm of the bell crank lever 70 is provided with a slot for the reception of a block 74 pivoted on a pin 76 secured to a slide 78 mounted for vertical sliding movement in suitable guides in the frame. The upper end of the slide 78 carries a cam roll 80 which engages a cam groove 82 in the cam disk 62.

The machine is also provided with a cutting device for severing the end portion of the thread between the gripping device and the work at the completion of the fastening operation. In the present embodiment of the invention this cutting device is normally out of thread cutting position, and is moved into thread cutting position at the proper time in a cycle of operations. In the construction illustrated the thread cutting device comprises pivotally connected shear blades 84 and 86 which are normally supported above the gripping device. The blade 84 of the cutting device has no pivotal movement, this blade being formed upon an arm 88 secured to a vertically movable slide hereinafter described. The movable blade 86 of the cutting device is formed on a lever 90 which is pivoted to the arm 88 by means of a screw stud 92. The blades of the cutting device are normally held in relatively open position by means of a spiral spring 94, one end of which is secured to the lever 90 and the other to the arm 88. The movement of the lever 90 in a direction to open the blades is limited by contacting lugs 96 and 98 formed respectively on the lever 90 and the arm 88. The cutting device is normally supported out of thread cutting position, as illustrated clearly in Fig. 1. In order to permit the thread cutting device to be moved downwardly into thread cutting position, the arm 88 thereof

is secured to a slide 100 which is mounted for upward and downward sliding movement in suitable guides in the machine frame. To permit the cutting device to be 5 adjusted vertically with relation to the slide, the arm 88 is provided with a slot 102 and the cutting device is secured to the slide by means of a screw 104 passing through the slot and screwed into a projecting portion 10 of the slide. This provision for adjustment enables the cutting device to be brought into the proper cutting position with relation to the thread.

When the work has been pushed forward 15 with relation to the gripping device to withdraw the gripping device from the thread loop of the seam, and to draw the free end of the thread beneath the loop, the cutting device is moved downwardly from the position 20 in which it is shown in Figs. 1 and 2, to bring the blades of the cutting device which are then open on opposite sides of the thread extending between the gripping device and the work, and the blades thereof are then 25 closed to sever the thread. The mechanism for imparting the vertical movements to the cutting device to place said device in and out of thread cutting position at the proper times in the operation of the machine, comprises a cam actuated lever 108 pivoted on 30 the stud 110 and provided with a recess at its forward extremity which receives a block 112 journaled on a screw stud 114 secured to the slide 100. At its rear end the lever 108 carries a roll 116 which engages a cam 35 groove 118 in the cam disk 24^a. When the cutting device has been moved downwardly into cutting position, the movable blade thereof is moved relatively to the fixed blade 40 to sever the thread by the engagement of the forwardly extending arm of a lever 120 with a roll 122 mounted on the upper end of the lever 90. The lever 120 is pivoted upon a vertical stud 124, and is provided 45 with a cam roll 126 which engages a cam groove 128 in the cam disk 62 whereby the lever is actuated at the proper time in the operation of the machine to close the blades of the cutting device. After the thread is 50 severed between the gripping device and the work, the jaws of the gripping device are opened to release the portion of the thread which is gripped between them, and the parts are restored by their respective operating mechanisms to the relative positions 55 illustrated in Fig. 1.

The main shaft 26 of the machine is driven by means of a belt passing about a pulley 130 loosely mounted on the shaft. The pulley 60 130 is connected with the shaft by means of a clutch mechanism which is controlled by a treadle, so that each time the treadle is depressed the clutch is engaged, and the shaft is driven a part of a revolution and is then 65 automatically stopped in a definite position.

When the work has been presented to the machine, and manipulated to insert the jaws of the gripping device beneath a loop of thread of the seam, the treadle is depressed by the operator, thereby engaging the clutch 70 and starting the machine. The shaft is rotated through part of a revolution sufficient to open the jaws of the gripping device and to project the thread receiving hook between said jaws into thread receiving position, as 75 illustrated in Fig. 8. The shaft is then automatically stopped, so that the end portion of the thread may be manipulated to locate the same in proper tying relation to the gripping device and then placed in the hook 42 80 by the operator. After this has been done, the operator again depresses the treadle to start the machine, and the shaft rotates through the remaining part of a revolution to complete the thread fastening and cutting 85 operation, and is automatically stopped when the parts of the machine are restored to their initial positions. The clutch mechanism for connecting the pulley with the shaft 26 comprises a cylindrical collar 132 90 secured in any suitable manner to the shaft 26. A sleeve 136 is secured to and preferably formed integral with the collar 132, said sleeve extending to the left (Fig. 3) from the collar and projecting within a cylindrical recess 138 in the pulley 130. The sleeve 136 is slabbed off or flattened at the points indicated at 140, and clutch rolls 142 are arranged between the flattened portions of the sleeve 136 and the adjacent face of the 100 recess 138 in the pulley 130. The construction and arrangement of the parts are such that when the clutch rolls occupy a central position with relation to the flattened portions of the sleeve the pulley 130 will rotate 105 freely about the sleeve, but that when the clutch rolls are moved in the direction of rotation of the pulley with relation to the sleeve the rolls will frictionally engage the flattened portions of the sleeve and the adjacent face of the recess in the pulley 130, and cause the driving of the sleeve by the pulley. In order to actuate the clutch rolls to clutch the pulley to the sleeve, and to unclutch the pulley therefrom, a collar 144 is mounted on 110 the sleeve 136 between the collar 132 and the adjacent portion of the pulley 130, and is provided with a series of spaced lugs projecting to the left (Fig. 3) into the recess in the pulley 130, and the clutch rolls 142 are 115 located in the spaces between these lugs. The collar 132 is provided with pins 148 which project laterally therefrom and engage in slots 150 in the collar 144. The collar 132 is connected with the collar 144 by 120 means of a tension spring 152 located in an arc shaped recess in the collar 144 and attached at one end to a pin 154 secured in the collar 144, and at the other to a pin 156 secured in the collar 132. The spring 152 nor- 125 130

5 mally tends to turn the collar 144 with relation to the collar 132 in a direction to cause the clutch rolls to be moved into clutching engagement with the pulley 130 and the sleeve 136, and thereby to cause the pulley to drive the shaft 26. When, therefore, the collar 144 is free to be actuated by the spring, the shaft is continuously rotated by the pulley, and during the rotation of the shaft the 10 pulley 130, the collar 144, and the collar 132 rotate in unison.

The pulley is unclutched from the shaft, and the rotation of the shaft is arrested, by stopping the rotation of the collar 144. The 15 continued rotation of the collar 132, due to the momentum of the machine, then causes a relative movement between the clutch rolls 142 and the flattened clutch surfaces of the sleeve 136 such as to unclutch the pulley 20 from the sleeve. When the rotation of the collar 144 is arrested, the rotation of the collar 132 on the shaft is resisted by the spring 152, which will tend to arrest the rotary movement of the shaft. Should the resistance of this spring not be sufficient to stop the forward movement of the shaft, the relative movement between the collar 144 and the collar 132 will cause the clutch rolls 142 to wedge between the rear portions of the 30 clutch faces 140 of the sleeve 136 and the adjacent face of the recess in the pulley 130, and thereby arrest the rotation of the shaft.

The rotation of the collar 144 is arrested to throw the clutch rolls out of clutching 35 engagement with the sleeve 136 and with the pulley 130 by interposing a projection on a stop block 158 in the path of a lug or projection 160 formed on the collar 144. In the illustrated embodiment of the invention 40 there are two projections 160 on the collar 144 arranged substantially a quarter of a revolution apart. Both these lugs co-operate with the projection on the stop block 158 in substantially the same manner, and 45 are provided to enable the clutch to be disengaged and the rotation of the shaft arrested in two different positions of the shaft. The stop block 158 is slidably mounted on the outer end of a rod 162 and is 50 yieldingly held in engagement with an abutment or shoulder 164 on said rod by a coiled spring 166 surrounding the rod and interposed between the block and a nut 168 threaded on the rod. The lower end of the 55 rod is threaded into the upper arm 170 of a lever 170-172 attached to a shaft 174 which is journaled in bearings in the frame of the machine, and the block is moved to carry the projection thereon into and out 60 of the path of the projections 160 by swinging the lever. The lever 170-172 is swung in a direction to carry the projection on the stop block 158 into the path of one of the projections 160 by a coiled spring 176 seat- 65 ed at one end in the arm 172 of the lever,

and engaging at its outer end a projection 178 on the frame. The movement of the lever 170-172 under the action of the spring 176 is limited by a stop arm 180 on the frame which is arranged to be engaged by 70 an abutment screw 182 threaded into the arm 170 of the lever. Connecting mechanism is provided between the lever 170-172 and the treadle, which mechanism is so constructed and arranged that by the depression of the treadle the lever 170-172 is 75 swung in the direction to carry the projection on the block 158 out of the path of the lugs 160. Said mechanism comprises an arm 184 fixed to the shaft 174 and provided 80 with a pin 186 adapted to be engaged by a shoulder 188 formed by an annular recess in an arm 190 pivoted at 192 to the end of the forwardly extending arm of a lever 194. The arm 190 is normally held in position 85 with the lateral face of the recess in said arm engaging the pin 186 and with the shoulder 188 below the pin by a coiled spring 196 interposed between a shoulder on said arm and the forward arm of the lever 90 194. The lever 194 is pivoted on a shaft 198 and is connected with a treadle (not shown) by means of a treadle rod 200. The rear arm of the lever 194 is lifted upon the release of the treadle by a coiled spring 202. 95 In the drawings the parts are shown in the positions which they assume when the treadle is released and the clutch is disengaged. When the treadle is depressed, by the engagement of the shoulder 188 with the pin 100 186, the shaft 174 will be swung in its bearings, thereby swinging the lever 170-172 in a direction to carry the projection on the stop block out of engagement with the lug 160. In order to disconnect the lever 194 105 from the lever 170-172, so that the stop block may be swung forwardly to restore the projection thereon to the path of one of the lugs 160 while the treadle is depressed, the arm 190 is provided with an extension 204 110 which projects upwardly to a point adjacent the periphery of the cam disk 24^a into position to be engaged by either of the lugs 206 on the cam disk. The engagement of one of these lugs with the extension 204 will 115 swing the arm 190 rearwardly so as to release the shoulder 188 from beneath the pin 186, and when this occurs the lever 170-172 is actuated by the spring 176 to swing the stop block forwardly, thereby bringing the 120 projection thereon into the path of one of the lugs 160.

When the driving pulley has been unclutched from the main shaft, and the rotation of the shaft has been arrested, the collar 132 and the shaft are held from reverse rotation under the action of the spring 152 by a pawl 208 which engages one of a series of teeth 210 formed on the collar 132. There are two sets of teeth on the collar 132 ar- 125 130

ranged substantially a quarter of a revolution apart and corresponding to the two projections 160 on the collar 144, and the pawl 208 coöperates in the same manner with both these sets of teeth. The pawl 208 is pivoted upon a screw stud 212 secured to the arm 170 of the lever 170—172, and is acted upon by a leaf spring 214 mounted on said arm.

10 As stated above, the two projections 160 and the two series of teeth 210 are arranged substantially 90° apart on the peripheries of their respective collars. When the work is first presented to the machine, the parts 15 of the machine occupy the positions illustrated in Figs. 1, 2, 3, 4 and 5 of the drawings. When the work has been positioned as shown in Fig. 7, the operator depresses the treadle, thereby releasing the projection 20 on the stop block from the projection 160 which it engaged, and allowing the clutch to be actuated to clutch the driving pulley to the main shaft of the machine. The rotation of the shaft will bring the first 25 or lower projection 206 into engagement with the extension 204 on the arm 190 before the second lug 160 reaches a point opposite the projection on the stop block, to release the shoulder 188 on said arm from the pin 186, and permit the shaft 170—172 to be actuated to swing the stop block forwardly to bring the projection thereon into the path of the second lug 160. The main shaft of the machine will therefore rotate 30 a quarter of a revolution, or until the second lug 160 engages the projection on the stop block. During this part of the revolution of the shaft, the jaws of the gripping device are opened, and the thread receiving 35 hook 42 is projected between said jaws, thereby bringing the hook and the gripping device into the relative positions shown in Fig. 8. The operator then draws the end portion of the thread under the gripping 40 device and over the thread loop beneath which the gripping device is inserted, places the end of the thread in the hook 42 and releases the treadle, so that the lever 194 may be actuated by the spring 202 to 45 swing the forward arm of the lever downwardly and thereby bring the shoulder 188 on the arm 190 beneath the pin 186. Then when the treadle is again depressed the clutch will be engaged to rotate the shaft 50 through a part of a revolution, and the stop mechanism will act to disengage the clutch and arrest the rotation of the shaft in substantially the same manner as before. After the second depression of the treadle, however, the shaft will execute substantially 55 three-quarters of a revolution before it is brought to rest. During this three-quarters of a revolution of the shaft, the thread fastening and cutting devices are actuated to 60 tie the end of the thread and to sever the 65

thread close to the work, and are then restored to their initial work receiving positions.

While the machine embodying the present invention as illustrated and described is 70 constructed and arranged to tie or fasten the free end of the thread in a particular manner, it is to be understood that the machine may be employed in fastening the end 75 of the thread in other ways than that shown in this application, and that the manner in which the thread is fastened will vary with the character of the seam, and with variations in the way in which the work is presented to the machine. 80

It is also to be understood that the invention is not limited to the particular construction and arrangement of parts of the illustrated embodiment of the invention, but that the invention may be embodied in any 85 form within the scope of the claims.

Having explained the nature and object of the invention, and having specifically described a machine embodying the same in its preferred form, what is claimed is:— 90

1. A thread end fastening machine, having, in combination, a device constructed for insertion beneath a thread loop forming a part of a seam for drawing the free end of the thread at the end of the seam beneath 95 the loop, and means for relatively actuating said device and the work to withdraw the device from the loop and thereby draw the free end of the thread beneath the loop.

2. A thread end fastening machine, having, in combination, a gripper for insertion beneath a loop of thread forming part of a seam, and means for relatively moving the work and the gripper to withdraw the gripper from the loop and thereby draw the 100 free end of the thread beneath the loop to fasten the same. 105

3. A thread end fastening machine, having, in combination, a gripper for insertion beneath a loop of thread forming part of a seam, comprising relatively movable thread 110 gripping jaws, means for relatively actuating the jaws of the gripper to receive and grip the free end of the thread, and means for relatively moving the work and the gripper to withdraw the gripper from the loop and thereby draw the free end of the thread beneath the loop to fasten the same. 115

4. A thread end fastening machine, having, in combination, means for supporting the work in fastening position, and means for drawing the free end of the thread at the end of a seam beneath a loop of thread forming part of the seam to fasten the same. 120

5. A thread end fastening machine, having, in combination, thread gripping means for insertion beneath a loop of thread forming part of a seam, means for placing the end of the thread in position to be seized by the thread gripping means, and means 125 130

for relatively moving the thread gripping means and the work to withdraw the thread gripping means from the loop and thereby draw the free end of the thread beneath the 5 loop to fasten the same.

6. A thread end fastening machine, having, in combination, a device for drawing the free end of the thread at the end of a seam beneath a loop of thread forming part of the 10 seam constructed for insertion beneath the loop, means for relatively moving said device and the work to withdraw the device from the loop and thereby draw the free end of the thread beneath the loop, and means 15 for severing the free end of the thread between said device and the work.

7. A thread end fastening machine, having, in combination, means for fastening the free end of the thread at the end of a seam, 20 to a thread loop forming part of the seam, and means for severing the free end of the thread close to the work.

8. A thread end fastening machine, having, in combination, means for fastening the 25 free end of the thread at the end of a seam to a thread loop forming part of a seam, and a thread cutting device for severing the free end of the thread upon the completion of the fastening operation.

30 9. A thread end fastening machine, having, in combination, means for fastening the free end of the thread at the end of a seam to a thread loop forming part of a seam and a thread cutting device for severing the free 35 end of the thread upon the completion of the fastening operation normally supported out of thread cutting position, and means for moving said thread cutting device into and out of thread cutting position.

40 10. A thread end fastening machine, having, in combination, a device for drawing the free end of the thread at the end of a seam beneath a loop of thread forming part of the seam constructed for insertion beneath the said loop, and a thread finger about which the free thread is drawn in placing the work in thread fastening position.

50 11. A thread end fastening machine, having, in combination, a device for drawing the free end of the thread at the end of a seam beneath a loop of thread forming part of the seam, constructed for insertion beneath said loop, and a thread finger about which the free thread is drawn in placing the work in thread fastening position, arranged for adjustment with relation to said device.

55 12. A thread end fastening machine, having, in combination, a thread gripper for insertion beneath a loop of thread forming part of a seam, a pusher for pushing the

work forward with relation to the gripper to withdraw the gripper from the loop and thereby draw the free end of the thread beneath the 65 loop, and means for actuating the pusher.

13. A thread end fastening machine, having, in combination, a thread gripper for insertion beneath a loop of thread forming 70 part of a seam, a pusher for engaging the work to push the work forward with relation to the gripper, means for actuating the pusher to push the work off the gripper to draw the free end of the thread beneath the 75 loop and to draw the thread taut between the gripper and the work.

14. A thread end fastening machine, having, in combination, relatively movable thread gripping jaws for insertion beneath 80 a loop of thread forming part of a seam, a thread receiving hook, means for advancing the hook between the jaws in position to receive the end of the thread and for thereafter retracting the hook to draw the thread 85 between the jaws, means for opening and closing the jaws to receive and grip the thread, and means for relatively moving the work and the gripping jaws to withdraw the jaws from the loop and thereby draw the 90 free end of the thread beneath the loop to fasten the same.

15. A thread end fastening machine, having, in combination, a thread gripper for insertion between a loop of thread forming 95 part of a seam, a device for placing the free end of the thread in position to be gripped by the thread gripper, and means for relatively actuating the gripper and the work to withdraw the gripper from the loop, and thereby draw the free end of the thread 100 beneath the loop to fasten the same.

16. A thread end fastening machine, having, in combination, a thread gripper for insertion beneath a loop of thread forming 105 part of a seam, a device for placing the end of the thread in position to be gripped by the thread gripper, means for stopping the machine when the said device has been brought to thread receiving position, and 110 means for stopping the machine at the completion of the thread fastening operation.

17. In a thread end fastening machine, a frame and a thread grasping device for grasping the free end of the thread mounted 115 on the frame and constructed and arranged for insertion beneath a thread loop forming part of a seam and adapted when withdrawn from the loop to draw the free end of the thread beneath the loop to fasten the same. 120
